COWBOY BOOT UPPER

Julius Z. Miller and Lloyd M. Easterling,
Clarksville, Tenn.

Application September 22, 1947, Serial No. 775,420

2 Claims. (Cl. 36—2)

1

This invention relates to new and useful improvements and structural refinements in boots, more particularly, in children's boots, and the principal object of the invention is to provide what may be referred to as cowboy boot upper, which may be effectively and realistically employed in association with conventional boots or shoes, so as to simulate the appearance of cowboy boots.

A further object of the invention is to provide a cowboy boot upper of the character above outlined, which will eliminate the disadvantages of high heels and narrow toes, such as are commonly found in cowboy boots.

Another object of the invention is to provide a cowboy boot upper which is simple in construction and which may be quickly and easily applied to or removed from the boot or shoe.

An additional object of the invention is to provide a cowboy boot upper which is pleasing and realistic in appearance, which will readily lend itself to economical manufacture and which will possess considerable appeal to children, from the viewpoint of its ornamental novelty.

With the above more important objects in view, and such other objects as may become apparent as this specification proceeds, the invention consists essentially of the arrangement and construction of parts as illustrated in the accompanying drawings, in which:

Figure 1 is a perspective view of the invention, showing the same in situ on the shoe.

Figure 2 is a cross-sectional view, taken substantially in the plane of the line 2—2 in Figure 1, and

Figure 3 is a cross-sectional view, taken substantially in the plane of the line 3—3 in Figure 1.

Like characters of reference are employed to designate like parts in the specification and throughout the several views.

Referring now to the accompanying drawings in detail, the invention consists of a cowboy boot upper, designated generally by the reference character 10, the same embodying in its construction what may be referred to as a legging 11 having a flattened tubular calf portion 12 and an open, enlarged base portion 13.

The legging 11 is made from any suitable material such as leather or the like, and may be formed integrally, or if desired, from individual portions or pieces sewn or otherwise secured together as at 14. Also, suitable reinforcing strips 15 may be provided on the legging 11, as will be clearly apparent from the accompanying drawings.

2

The base portion 13 is adapted to fit over the upper of a conventional shoe 16, and the calf portion 12, of course, extends upwardly from the base portion, terminating at its upper end in a pair of flexible wings 17. The entire legging is held in position on the shoe 16 by means of a strap 18, one end of which is rigidly secured as at 19 to one side of the base portion 13, while its remaining end is releasably engageable with a clasp 20 provided on the relatively opposite side of the base portion 13. As will be clearly apparent from the accompanying Figure 1, the strap 18 is adapted to pass under the shank 21 of the shoe 16, whereby the entire legging 11 is retained in position. Finally, it should be explained that for purposes of realistic appearance, the side portions of the legging are provided with a suitable design 22 which usually characterizes cowboy boots.

When the invention is placed in use, the legging 11 is first applied to the leg by passing the foot downwardly through the calf portion 12 and through the base portion 13, whereupon a conventional shoe or boot may be applied to the foot and the legging 11 drawn downwardly so that the base portion 13 thereof engages the shoe upper, as has been already explained. The strap 18 is then passed under the shank 21 of the shoe 16 and secured by the clasp 20, and it will be understood that in this particular manner, the legging may be applied to the leg without the necessity of passing the shoe 16 through the narrow calf portion 12. The legging is, of course, removed by simply reversing the procedure above outlined.

It is believed that the advantages and use of the invention will be clearly apparent from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention claimed.

Having described the invention what is claimed as new is:

1. A gaiter simulating a cowboy boot upper comprising a pair of coextensive self-supporting and shape-retaining side panels including lower portions adapted to extend forwardly over the instep portion of a shoe, said side panels being joined together along the opposite side edges to form a unitary substantially tubular gaiter having an

ankle-embracing portion and a shoe instep covering portion, the upper end of each side panel having an edge curving upwardly towards its mid-portion which is positioned at the sides of the leg of the wearer, the opposite ends of said edge terminating at the upper ends of said joints and being located at the front and back of the wearer, said panels being adapted to extend substantially above the ankle and substantially below the knee of the wearer to approximately a midpoint there-between, the ankle embracing portion being adapted to loosely fit the ankle and the upper part of the gaiter loosely embracing the lower leg portion of the wearer, and fastening means for securing the gaiter to a shoe by holding the edges of the lower portions of the panels upon the upper surface of the shoe instep portion, whereby said gaiter may be applied to a variety of sizes of shoes and may accommodate different sizes of wearers' legs.

2. An article of footwear simulating a cowboy boot upper comprising a gaiter having a pair of coextensive self-supporting and shape-retaining side panels, the upper portions of said panels being outwardly flared and provided with upwardly curving edges from opposite ends to their mid-points, the lower ends of said panels having instep portions adapted to extend forwardly over the instep portion of a shoe, means for permanently joining the opposite side edges of said panels to form a unitary substantially tubular gaiter having ankle and lower leg embracing portions and shoe instep covering portion, said upper edges having reinforcing strips along their length, the side panels being so proportioned that the upper edges terminate substantially above the ankle and substantially below the knee of the wearer, said ankle portion and said lower leg portion being adapted

to loosely embrace the ankle and lower leg of the wearer to provide a non-clinging covering therefor, and a fastener for securing the gaiter to a shoe with the lower edges of the panel instep portions resting upon the upper surface of a shoe instep portion, whereby said gaiter may be applied to a variety of sizes of shoes and may accommodate different sizes of wearers' legs.
